VICE FOR HOLDING WORKPIECES OF DIVERSE SHAPES

Gordon Francis Staples, East Kilbride, and Robert Mitchell, Castle Bromwich, Birmingham, England

Application November 23, 1953, Serial No. 393,910

5 Claims. (Cl. 81—38)

This invention concerns vises.

It is frequently the practice in machine shops for special jigs and fixtures to be designed and made for holding each different one of the majority of differently shaped components which require machining. This practice, particularly in machine shops where most components are manufactured on a batch production basis or where very small numbers of like components are involved, is highly uneconomic because it is very rare that a special jig or fixture can be used or be adapted for use for holding a different component.

The main object of the present invention is to provide a vise which can be quickly and inexpensively adapted for holding varied components of diverse shapes, and a further object of the invention is that such vise should be also capable of speedy conversion to a vise of standard type.

According to the present invention a vise includes for one or both jaws, holder means capable of adjustable location thereon and attachment thereto, locator means slidably held by each said holder means, each capable of being shaped at one end to suit the component to be gripped, and one or more thereof being shaped at the other end to abut means which allows of movement thereof to compensate for slight variation in component size before the gripping pressure of the vise becomes effective.

More particularly in accordance with the invention a vise has vertical serrations at the front of the jaws thereof, there being provided as auxiliary equipment, for each jaw, two holders each having like vertical serrations on the rear face thereof to enable same to be adjustably located and clamped in position against the jaw, sets of locators, four per set, each locator being capable of slideable engagement in a standard bore in its respective holder to lie longitudinally of the vise when the holder is in position and being shaped to suit the component to be gripped, and, behind each jaw, a rocker, pivoted between the two locators at that side of the vise and in which the rear end of each said locator is adapted to nest, said rockers allowing slight compensatory movement of said locators for variation in component size, before the gripping pressure of the vise becomes effective.

Preferably, in addition to said holder means, plain plates are provided as an alternative thereto, so that the vise may be converted to standard type.

An adjustable clutch may conveniently be provided to ensure a constant gripping pressure on each component.

The invention will be described further by way of example with reference to the accompanying drawings, in which:

Fig. 1 is an elevation of a vise constructed in accordance with the invention and holding a selected component;

Fig. 2 is a plan corresponding to Fig. 1, and

Fig. 3 is a fragmentary plan showing the vise converted to standard type.

Fig. 4 is a fragmentary, vertical transverse section on the line 4—4 in Fig. 1.

2

The vise is basically of the normal type comprising a body 11 by means of which it can be secured to a machine tool table, a lead screw 12 mounted in the body 11, a fixed rear jaw 13 and a front jaw 14 carrying a nut 15 which engages with the lead screw 12 thus enabling the jaw 14 to be adjusted by turning a handle 16 secured to the forward end of the lead screw 12.

The confronting faces of the jaws 13, 14 are vertically serrated and for each such serrated jaw face is provided 10 a pair of holders 17 correspondingly serrated on their faces so that they may be clamped rigidly in position on the serrated vise jaw face by means of a bolt 18 passing therethrough to engage with a nut 19 located in a T-slot 20 transversely of the vise jaw, at varying distances one 15 from the other. In the vise illustrated, which is a six-inch vise, the width of the jaws 13, 14 is such that the holders 17 can be brought up into contact with each other, or spaced one from the other up to an approximate maximum of four inches.

20 Each holder 17 has a square hole therethrough which lies longitudinally of the vise and with one diagonal vertical when the holder is in position. The upper corner of the hole just breaks the top surface of the holder. Each hole accommodates a locator 21 having a square cross-section with a very small clearance, of the order of one-thousandth of an inch, to give a close sliding fit. Each locator 21 is of such length as to protrude from the holder 17 at both sides, the holder 17 standing above the vise jaw to allow this. That end of each locator 21 extending 25 from the rear serrated face of its respective holder 17 is machined to an accurate spherical radius, whilst the front end of each locator 21 is machined, as will be described later, to grip the component.

Each vise jaw has rotatably mounted, by means of a 30 socket head cap screw 22, on the longitudinal center line of the vise, a rocker 23. One face of each rocker 23 lies just behind the serrated face of the vise jaw on which it is mounted and each side thereof is machined at an angle of about seven degrees to the front of the vise jaw, 35 receding from the latter as it extends towards the side of the vise. A cylindrical groove 24 at the same angle is provided in the face of each rocker 23, the radius of the groove being the same as that to which the rear end of each locator 21 is machined. The rockers 23 are hardened and ground.

40 In order to adapt the vise for gripping the component 45 illustrated the first step is to set the holders 17 at the correct spacing and then to lock them in position against the vise jaws. Next, the locators 21, of suitable length, are placed in the square holes of the holders 17. 50 Each rocker 23 is locked in position with its longitudinal center line square to the axis of the vise screw 12. This operation is facilitated by the provision of two bushed holes 26, 27 one in the rocker and one in the vise jaw, accurately positioned so that when in alignment, a pin may be accommodated therein to locate the rocker 23 in the desired datum position. Each locator 21 is then slid rearwardly until its spherical end seats in the cylindrical groove 24 in the respective rocker 23. 55 The locators 21 are then locked in position by means of grub screws 21a provided in the holders 17.

60 Then, with the vise fixed on the table of the machine tool, which may for instance be a milling machine, the front ends of the locators 21 are machined at the correct angle for gripping the component. In the case of 65 the component illustrated the machining of the end faces of the locators 21 is a simple procedure involving merely the swivelling of the milling machine table to the necessary angle and surfacing same to cause the respective locators 21 to move past an end mill fixed in the machine head. In other cases it may be desirable to 70 mark out the end of each locator 21 prior to machining

to the line. It will normally be preferable for each locator 21 subsequently to be removed and hardened and ground.

In use, the locators 21 are released by slackening off the grub screws 21a in the holders 17, the pin locating the rocker is then removed and the socket head cap screw 22 holding the rocker 23 slackened off. The component 25 which, in the example illustrated, has a flat lower face, is supported between the opposing pairs of locators 21 on a parallel 28 and the movable vise jaw 14 brought up towards the other jaw 13 by turning the lead screw 12. The locators 21 abut the angular faces of the component 25 and the reaction force brings their rear ends into hard abutment with the grooves 24 in the respective rockers 23. Each rocker 23, being free to rotate, will be self-adjusting to the component 25 and will thus allow for small variations in the size of the latter. As soon as the gripping force reaches a certain magnitude the reaction force of the rocker 23 on to the locators 21, which due to the inclination of the front face of the rocker 23, has a component transversely of the vise, causes the locators 21 to lock in the square holes, with which, it will be remembered, they have a very close fit.

In order that the gripping force of the vise on the component should be constant for each component, an adjustable clutch 36 may be provided in the driving arrangement of the lead screw 12. In the illustrated embodiment of the invention, the normal handle 16 located on the square end of the lead screw 12 is supplemented by a further handle 29 carried by the end of an upwardly inclined split shaft 30, 31 of short axial length journaled in a housing 32 cast integrally with a bearing housing 33 of a lead screw ball race. A driving connection is provided between the lower half 30 of this shaft and the lead screw 12 by a pair of bevel gears 34, 35. The clutch 36 is of the dog type with very shallow teeth having inclined sides and a thrust washer 37 is screwed into the end of the shaft housing 32, a helical spring 38 being disposed between a thrust race 39 in the face of the washer 37 and one half of the clutch which is formed integrally with that half of the shaft to which the handle 29 is attached. The spring 38 can be loaded variably by screwing the thrust washer 37 in or out by means of a special tool thus enabling the load at which the clutch will slip to be correspondingly varied. By this means a constant gripping force on the component can be ensured.

The second handle 29 also avoids the difficulty of the other handle 16 fouling the table. Either handle, of course, may be removed when not in use.

As an alternative to the holders described, flat hardened and ground plates 40 may be provided with serrations to fit the serrations on the vise jaws as shown in Fig. 3. The length and depth of the plates 40 are commensurate with the length and depth of the vise jaws and when bolted in position using the bolts 18, the vise is capable of use as a standard vise.

The vise is capable of universal adaptation and by way of further example, four types of component of widely varying shapes will now be described to illustrate its adaptability.

A thin template having a variously curved perimeter can be held efficiently in the vise. In this case the end of each locator is conveniently provided with a machined shoulder, the template being thereby provided with four supporting surfaces on which it can be rested while it acts as a guide for the marking out of the locator ends.

A double shrouded turbine blade can be conveniently held in the vise for the datum milling of facets. For this purpose special locators would be provided having specially shaped slots extending transversely across their end faces to receive the sides of the turbine blade.

Small components may be held in the vise two at a time, one between each opposed pair of locators.

For holding circular components, particularly hollow cylindrical castings with thin walls, a set of standard lo-

cators may be used having their end faces machined at an angle of forty-five degrees.

Although the invention has been particularly described with reference to drilling and milling operations it can be used to equal advantage for instance on grinding machines, and numerous modifications in its construction may easily suggest themselves to a person skilled in workshop technology, and the scope of the invention, therefore, is to be understood as not limited in any way to the constructional details of the particular embodiments described.

We claim:

1. A vise comprising a body, a fixed jaw fixedly mounted to said body, a sliding jaw mounted for movement towards and away from said fixed jaw along said body, a lead screw journaled in said body and engaging a nut in said sliding jaw whereby movement of said sliding jaw may be effected, a pair of laterally spaced holders on the confronting face of at least one of said jaws, a locator mounted in each holder for longitudinal sliding motion, a rocker on said jaw rearwardly of said locators and being centrally pivoted, the rear faces of said locators abutting against said rocker on opposite sides of said pivot.
2. A vise comprising a body, a fixed jaw fixedly mounted to said body, a sliding jaw mounted for movement towards and away from said fixed jaw along said body, a lead screw journaled in said body and engaging a nut in said sliding jaw whereby movement of said sliding jaw may be effected, a pair of laterally spaced holders on the confronting face of at least one of said jaws, a locator mounted in each holder for longitudinal sliding motion, a rocker on said jaw rearwardly of said locators and being centrally pivoted, the sides of said rocker being angular, the rear faces of said locators abutting against said rocker on opposite sides of said pivot.
3. A vise comprising a body, a fixed jaw fixedly mounted to said body, a sliding jaw mounted for movement towards and away from said fixed jaw along said body, a lead screw journaled in said body and engaging a nut in said sliding jaw whereby movement of said sliding jaw may be effected, a pair of laterally spaced holders on the confronting face of at least one of said jaws, a locator mounted in each holder for longitudinal sliding motion, a rocker on said jaw rearwardly of said locators and being centrally pivoted, the rear faces of said locators abutting against a forward face of said rocker on opposite sides of said pivot, said abutting faces being shaped as a ball and socket joint.
4. A vise comprising a body, a fixed jaw fixedly mounted to said body, a sliding jaw mounted for movement towards and away from said fixed jaw along said body, a lead screw journaled in said body and engaging a nut in said sliding jaw whereby movement of said sliding jaw may be effected, two holders having standard bores secured to the confronting faces of each jaw, a locator slidably accommodated within each of said bores and disposed longitudinally of the vise, and a rocker pivoted behind each jaw on an axis between sliding axes of the two locators associated with each jaw and arranged so that the rear ends of said locators abut thereagainst to allow slight compensatory movement of said locators for variation in component size before the gripping pressure of the vise becomes effective.
5. A vise having vertical serrations at the front of the jaws thereof, there being provided as auxiliary equipment, for each jaw, two holders each having like vertical serrations on the rear face thereof to enable same to be adjustably located and clamped in position against the jaw, a locator provided for each holder, each locator being capable of slidable engagement in a standard bore in its respective holder to lie longitudinally of the vise when the holder is in position and being shaped to suit the component to be gripped, and a rocker pivoted behind each jaw on an axis extending between longitudinal

axes of the two locators associated with each jaw of the vise and in which rocker the rear end of each said locator is adapted to nest, said rockers allowing slight compensatory movement of said locators for variation in component size, before the gripping pressure of the vise becomes effective.
